DIRECTIONAL WIRELESS SYSTEM
EMPLOYING PULSES

William Spencer Percival, Ealing, London, England, assignor to Electric & Musical Industries Limited, Hayes, Middlesex, England, a company of Great Britain

Application November 16, 1938, Serial No. 240,602
In Great Britain November 16, 1937

5 Claims. (Cl. 250—20)

The present invention relates to wireless communication and direction finding systems in which the signals transmitted are in the form of pulses as distinct from a continuous wave transmission and relates also to wireless communication systems in which a carrier employing continuous waves has a pulse transmission superimposed thereon. The invention is concerned with the prevention of interference with reception of the signals, and with the application of certain interference suppression technique to provide receiving apparatus of a highly directional type.

There has previously been described, in the specifications of British Patents Nos. 467,263 and 468,994, a system for suppressing short pulses which interfere with the reception of carrier wave transmission. The system described in these specifications is of the type having an auxiliary receiver designed to discriminate in favour of interference and which serves to switch off the main receiver for short periods corresponding to each pulse of interference which exceeds a certain amplitude. It has been pointed out in the latter specification that the auxiliary receiver may be connected to a separate aerial located and orientated in such a way as to respond less to the wanted signal than does the main aerial and to be more sensitive to interference than the main aerial.

According to the present invention a system for the transmission of short pulses comprises means for the reception of the pulses in which pulses or interfering signals other than a specified pulse transmission are prevented from being received by a main channel by means of an auxiliary channel.

The invention will now be described by way of example with reference to the accompanying drawing which illustrates a receiving circuit according to the present invention.

Pulses sent out from different sources, or sets of pulses sent out from the same source are differentiated and selectively amplified by the means illustrated.

Terminal I_1 is the input terminal to a main channel and terminal I_2 is the input terminal to an auxiliary channel. These terminals are connected to the same or different receiving aerials $1, 3$ respectively. The main channel is relatively sharply tuned to the frequency of the carrier it is desired to receive, that is to say it has a relatively narrow pass band, whilst the auxiliary channel is relatively flatly tuned.

65 The auxiliary channel comprises a circuit $L_1 C_1$

tuned to the frequency of the desired carrier or to some other frequency. A valve V_1 acts as a mixer valve for mixing the oscillations from circuit $L_1 C_1$ with local oscillations fed from an oscillator V_2 through a condenser C_9 . In one example circuit $L_1 C_1$ is tuned to a frequency between 15 and 45 megacycles per second and the oscillator V_2 serves to produce an intermediate frequency of 4.8 megacycles per second.

The valves V_3, V_4, V_5 and V_6 are arranged to amplify at this intermediate frequency. Tuning of the intermediate frequency stages is effected with the aid of variable inductances L_4 and L_5 which are damped by means of resistances R_1 and R_2 . The tuning of the various stages may be staggered so that with the damping resistances the desired breadth of tuning is obtained. The pass-band for the intermediate frequency amplifier may be 150 kilocycles per second.

The output of the intermediate frequency amplifier is coupled to a diode detector V_7 the output of which passes through a filter to the inner grid of a heptode valve V_8 which constitutes the first valve of the main channel. The filter comprises shunt condensers C_5, C_6 and C_7 and series elements, each comprising a resistance and an inductance $R_3 L_7, R_7 L_8$ and $R_4 L_9$. The filter is so designed as to remove the carrier frequency of say 4.8 megacycles per second and to pass without substantial attenuation the modulation frequencies passed by the intermediate frequency amplifier, that is frequencies below about 75 kilocycles per second. It is also designed so as to avoid resonances which might cause transients to give rise to variations of an oscillatory character on the inner grid of valve V_8 . The output of valve V_8 is taken from terminals P to a receiver 2 of normal type which with the valve V_8 constitutes the main channel and passes a narrower band of frequencies than the intermediate frequency amplifier V_3, V_4, V_5 and V_6 .

A suitable positive bias is applied to the cathode of valve V_8 relative to its control grids by means of a resistance R_6 shunted by a by-pass condenser C_8 . A suitable voltage may be impressed between terminals V to make the cathode of the diode V_7 somewhat positive relatively to the anode thereof and thus to back-off the diode and prevent it passing current for signals below a predetermined amplitude.

The input terminal I_1 of the main channel is connected to the outer control grid of the valve V_8 through a band-pass delay network $L_{10} C_3 L_{11} C_4$ which is designed to give to the signals passed therethrough a delay equal to or slightly greater

55

than the delay introduced in signals passing from terminal I_2 to the valve V_8 .

The automatic volume control circuit for the auxiliary channel comprises, in this example, an additional intermediate frequency stage including a valve V_9 and a tuned circuit $L_{12} R_5$ connected to the output of valve V_8 . The valve V_8 is of such type that when given a low screen-grid voltage it operates as a limiter, partly by grid current damping and partly by anode current cut-off. The output of this valve V_8 is fed to a diode detector V_{10} and the output of the latter is fed from a filter F to the grids of one or more of the valves of the intermediate frequency amplifier V_3, V_4, V_5, V_6 .

The auxiliary channel is connected at terminal I_2 to an auxiliary aerial 3 which is either anti-directional to a specified pulse transmission or which is responsive to interfering signals or pulses arriving in the same direction as the specified pulse transmission but having different states of polarisation.

The operation of the circuit above described is as follows:

Whether the circuit $L_1 C_1$ is tuned to the same frequency as the main channel or to a different frequency, both terminals I_1 and I_2 receive the same transient interference and that in the auxiliary channel is detected at V_7 , if above the minimum amplitude (determined by the voltage at V_1) to which the detector V_7 is responsive, and is applied as a negative pulse to the inner control grid of valve V_8 . It is arranged by a suitable choice of valve and bias for V_8 that even a small transient interference signal is capable of cutting off the valve V_8 by arresting the flow of electrons therein. Since the delay in the main channel is equal to or slightly greater than that in the auxiliary channel, the amplification of valve V_8 and hence that of the main channel, will have been reduced substantially to zero by the time a transient reaches the outer control grid of valve V_8 from terminal I_1 .

The valve V_8 , by acting as a limiter, ensures that signals above a relatively low amplitude have no further effect upon the A. V. C. voltage developed. Moreover, since the energy content of transients of the same amplitude as a continuous wave is much smaller than the energy content of the continuous wave, transients of the maximum amplitude that can pass the limiter have but little influence on the A. V. C. voltage developed. Thus the A. V. C. voltage is mainly dependent upon the continuous waves and it can be arranged that the amplification of the intermediate frequency amplifier V_3, V_4, V_5, V_6 varies as the amplitude of continuous waves varies in such a way as to maintain the output of continuous waves from the valve V_6 substantially constant and small and that the action is substantially unaffected even by transients of very large amplitude.

The aerial 1 supplying the main channel may be arranged so as to be more sensitive than the other aerial to the desired signal 5. The latter aerial on the other hand may be made relatively more sensitive to transient interference by suitable location or orientation thereof. For example, the aerial of the auxiliary channel may be a length of wire taken close to a source of interference 7, the effect of which on the main channel it is required to eliminate.

The auxiliary aerial may also be made sensitive to pulse transmissions arriving from directions other than from the direction of the required signal pulse or to pulses polarised in a

manner other than the required signal pulse. Accurate location may thus be obtained of the direction of any object emitting or reflecting pulses. For example, pulses radiated by the ignition system of an aeroplane may be detected at a place on the ground and the bearing of the aeroplane accurately determined or pulses reflected by an aeroplane may be utilised to give an indication of the position of the aeroplane. As a further example, obstacles at sea may be located by applying short pulses to the water and observing the directions from which pulses are reflected back again. Reflections from directions other than those which are being observed, and any other interfering pulses, will be suppressed as previously described. It is of course assumed that the unwanted pulses do not, in general, arrive at the same instant as the wanted pulses, so that the main receiver is not disabled at the moment of reception of a wanted pulse.

When there exist a plurality of pulses or interfering signals which it is required to prevent the main channel from receiving, then it may be necessary to employ a plurality of auxiliary channels.

The auxiliary channel together with its associated aerial system may be made to respond appreciably to signals which emanate from directions making but small angles with the required signal so that the response of the main channel will be a maximum to the required signals, which maximum response decreases rapidly due to the action of the auxiliary channel. By this means there is furnished a direction finding system which operates on the maximum value of the required signal, and which maximum decreases rapidly on either side of the direction of the maximum signals.

By suitably biasing 4 a valve or valves of the receiver the latter may be made insensitive to signals below a predetermined amplitude value. Small signals and background noise may thus be suppressed, and with this arrangement the pulses used for transmitting may be given an increased time interval for each pulse, as the effect on the receiver depends upon the energy content of the whole pulse. Background noise which may be of a continuous character but have only a small amplitude will be eliminated by such biasing of a valve or valves of the receiver, the pulses being above such eliminated amplitude level and thus are unaffected thereby.

Apparatus according to the invention may be applied to receive, without mutual interference, one at a time, a number of pulse transmissions from different stations provided that these transmissions all differ in direction or plane of polarisation, and provided that the gaps between pulses are large compared with the width of each pulse so that the probability of pulses from different stations coinciding in time is reasonably small. The interval or gap between the pulses determines the frequency of the pulses and this frequency may be modulated as required.

A transmission system according to the present invention may utilize a continuous wave transmission and a system of pulses which both employ the same frequency band and thus two sets of messages may be transmitted, these being dealt with at the receiving end by two receivers, of which one receives only the continuous waves, while another receiver receives only the system of pulses.

Further, a plurality of pulse transmissions may be generated at a transmitter, which pulse trans-

missions are polarized in different planes and preferably arranged so that the separate pulse transmissions do not coincide in time. The transmissions may be separated out at the receiving station by receiving apparatus of the kind described above in which the main and auxiliary aerials can be adjusted to discriminate between signals arriving from the same direction but having different planes of polarization.

10 It may be desired to examine the shape or exact time of arrival of a signal pulse for certain purposes and a difficulty may arise here in the following way. The auxiliary receiver, particularly if it has a large amplification, may, due to noise and small disturbances, produce a varying control bias which varies the gain of the main receiver without actually switching it off, and this variation of gain will distort the wave form of the amplified pulses.

20 According to a further feature of the invention this difficulty is overcome by interposing a trigger device 6, such as a gas filled valve or a blocking oscillator, between the output of the auxiliary suppressor receiver and the point at 25 which the main channel is switched off, so that the main channel must be either normally operative or substantially inoperative, but cannot be continuously modulated by small variations in the output of the auxiliary receiver. Alternatively, the trigger device may be used to short 30 circuit the main channel. The recovery period of the trigger device must be reasonably short to avoid leaving the main receiver switched off for too lengthy periods. Under these conditions 35 the waveform of the pulses will be preserved and may be examined, for example, on a cathode ray tube, the image possibly appearing faint if the main receiver is being very frequently switched off.

40 I claim:

1. A radio receiving system including in combination a main receiving channel having a narrow response band and including a control tube, an auxiliary channel having a broad response band and including an amplifier and a rectifier, a directional antenna connected to said first channel, a second antenna connected to said auxiliary channel, means for preventing said rectifier from responding to signals below a predetermined level and permitting response to signals exceeding said level, means connecting said rectifier to said control tube so that rectified currents may be applied to said control tube to diminish the response of said main channel to 55 said excessive signals, and a second amplifier connected to said first-named amplifier, a rectifier connected to said second amplifier, and means connecting said last-named rectifier to said first-named amplifier to control the response thereof.

2. A radio receiving system including in combination a main receiving channel having a narrow response band and including a control tube, an auxiliary channel having a broad response band and including an amplifier and a rectifier, a directional antenna connected to said first channel, a second antenna connected to said

auxiliary channel, means for preventing said rectifier from responding to signals below a predetermined level and permitting response to signals exceeding said level, means connecting said rectifier to said control tube so that rectified currents may be applied to said control tube to diminish the response of said main channel to 5 said excessive signals, and a trigger device interposed between said rectifier and said control tube so that said main channel is substantially insensitive to small variations in the output of said auxiliary channel.

3. A radio receiving system including in combination a main receiving channel having a narrow response band and including a control tube, 15 an auxiliary channel having a broad response band and including an amplifier and a rectifier, a directional antenna connected to said first channel, a second antenna connected to said auxiliary channel, means for preventing said rectifier from responding to signals below a predetermined level and permitting response to signals exceeding said level, means connecting said rectifier to said control tube so that rectified currents may be applied to said control tube to 25 diminish the response of said main channel to said excessive signals, and means for preventing said main channel from responding to signals below a predetermined amplitude value.

4. A radio receiving system including in combination a main receiving channel including a delay circuit and a tube for controlling the response of said channel, an auxiliary channel including a rectifier, an antenna connected to said first channel, a second antenna connected to 35 said auxiliary channel, means for preventing said rectifier from responding to signals below a predetermined amplitude value and permitting rectification of signals of amplitude exceeding said value, means connecting said control tube and 40 said rectifier to diminish the response of said main channel to said signals of amplitude exceeding said predetermined value, and means for limiting the response of said main channel to signals of amplitude exceeding a second predetermined value.

5. A radio receiving system including in combination a main receiving channel including a delay circuit and a tube for controlling the response of said channel, an auxiliary channel 50 including an amplifier and a rectifier, a directional antenna connected to said first channel, a second antenna connected to said auxiliary channel, means for preventing said rectifier from responding to signals below a predetermined amplitude value and permitting rectification of signals of amplitude exceeding said value, means connecting said control tube and said rectifier to diminish the response of said main channel to 55 said signals of amplitude exceeding said predetermined value, a second amplifier connected to said first-named amplifier, a second rectifier connected to said second amplifier, and means connecting said second rectifier to said first amplifier to control automatically the sensitivity 60 of said first amplifier.
